UNITED STATES PATENT OFFICE.

JOSEPH WOLFF, OF BROOKLYN, NEW YORK, ASSIGNOR TO SONORA PHONOGRAPH CORPORATION, A CORPORATION OF NEW YORK.

TALKING-MACHINE HORN.

1,392,037.

Specification of Letters Patent. Patented Sept. 27, 1921.

Application filed March 19, 1919. Serial No. 283,537.

To all whom it may concern:

Be it known that I, JOSEPH WOLFF, a subject of the King of Great Britain and Ireland, and residing at Brooklyn, in the 5 county of Kings, city and State of New York, have invented a certain new and useful Talking-Machine Horn, of which the following is a specification.

My invention relates to certain improvements in talking machine horns constructed of laminated material as hereinafter specified. This application is a division in part of my copending application filed April 28, 1915, and numbered serially 24,450 (series of 15 1915).

I have discovered that with the ordinary wood horns for talking machines, the sound waves penetrate the wood to a considerable degree, their force and color are more or less 20 lost, and that because of such absorption, relatively thin tones are produced with the consequent tendency to rattle on high notes and produce audible needle scratch. When producing great volume the scratch increases with the volume, part of the tone is 25 absorbed by the wood, and the scratch is apparently magnified.

I have found that by increasing the number of laminations of a veneer horn above 30 three, the number commonly employed, to a greater number, with the grain of each adjoining layer running in opposite directions, a greater volume of tone with more force and warmth is produced, but with less audible needle scratch than is possible with horns 35 of three laminations, for the reason that the tone is all projected through the mouth of the horn and thus the scratch is not magnified by any increased horn area but remains 40 relatively the same, and the greater volume and force of tone which is projected from the mouth of the horn drowns or smothers it, and this proportion of scratch to volume is always the same, even with varied 45 volumes produced by the use of different toned needles.

I likewise have discovered that by coating the outside of my improved horn with a material, such as silicate of soda, an improved 50 result is obtained. This is probably due to the fact that such sound waves as penetrate the material of the horn are reflected back.

I have also found that with a horn of 55 plural construction, the inner wall of which

will absorb some of the sound, and an outer wall, which will be to reflect the sound, a much better quality of sound will result than with the horns now in use.

The object of my invention therefore is to 60 produce a horn by means of which the scratch of the needle is made inaudible and by which richer and more natural tones are produced, and blasting and rattling vibrations are entirely eliminated on high tones. 65

These and further objects will more fully appear in the following specification and accompanying drawings considered together or separately.

My invention is illustrated in the drawings, 70 and described in the specification, in which corresponding parts in all the figures are designated by similar reference characters.

In the drawings,—

Fig. 1 is a horizontal section of a talking machine cabinet showing a horn in position;

Fig. 2 is a sectional view, on an enlarged scale, through a corner of one wall of the 80 horn;

Fig. 3 is a perspective view of a portion of a wall of a horn;

Fig. 4 is a detail edge view, on a very much enlarged scale, of a portion of a wall 85 of a horn showing a modification;

Fig. 5 is a detail sectional view of a horn showing another modification;

Fig. 6 is a perspective detail of another 90 modification.

In all of the above views similar reference characters designate corresponding parts in all of the figures.

In the drawings, 1 designates a talking machine cabinet of any well known form. 95 Within the cabinet is located a horn or diffuser, 2. The cabinet shown is of the type known as the "hornless," that is, one in which the horn is built in the cabinet and concealed from view. The horn is of generally rectangular cross section, and is built up of wall pieces 3, each composed of veneering.

In the embodiment shown in Figs. 1, 2, and 3 the walls are built up of five laminæ or layers 4, 5, 6, 7 and 8. The layers are arranged 105 in such a manner that the grain of each layer will run in a different direction from that of the next adjoining layer, and the layers are firmly secured together, as by gluing. The wall just described is com- 110

posed of a wood veneer, but it will be understood that other substances may be employed.

In Fig. 4 I have shown a modification of my invention in which eleven veneers are employed. The top and bottom layers are preferably of wood, and alternate layers may be of rubber, fiber, or any other suitable material, or all of the layers may be of wood. The wall, including the exposed ends of the layer, is coated as at 13 with a hard non-porous material such as silicate of soda.

In Fig. 5 I have shown an enlarged sectional view of a horn wherein five layers of veneering are employed. The exposed ends of the layers are covered by a binding 12 and the horn is given a coating of silicate of soda. The binding 12 may be and is preferably applied to the inner or small end 20 of the horn and to the outer or bell end thereof.

In Fig. 6 I have shown what I now consider the preferred embodiment of my invention. The walls of the horn are composed of nine layers of wood veneering. In each layer the grain of the wood runs in a direction at an angle to that of the adjoining layers. I prefer to build the horn of layers having the grain of alternate layers 30 running at right angles to the grain of the other layers. The layers may all be of the same wood, or they may be of different woods.

To the free ends of the horn both back 35 and front are applied a strip 14 of laminated wood. This strip is preferably glued in place and it may be of the same material and the same number of layers as the body of the horn, or it may be different material 40 and have a different number of layers, or it may be composed of a binding strip similar to the binding strip 12. If desired such strips 14 or 12 may be dispensed with. The horn may be coated as before.

I desire it to be understood that I do not wish to limit myself to any particular material used in the construction of my improved device, nor do I desire to limit myself to the exact number of layers to be employed above three. The walls may be 50 made of any ultimate thickness and veneer of any degree of thinness may be employed.

In operation, the sound waves set up by the vibrations of the diaphragm of the 55 producer, will traverse the horn from the back or small end to the flaring front and be projected into the atmosphere. Prac-

tically all of the sound will reach the outlet for the reason that the inner thin layer will be the only one which will absorb any considerable amount of sound which will nearly all be reflected by the next layer. The small amount of sound absorbed by the second layer will be turned back by the third, and so on to the outside. The more 65 layers in the walls, up to the point where the walls become so thick and heavy as to be unresponsive to the sound vibrations, the better will be the result.

In accordance with the provisions of the 70 Patent Statute, I have described the principles of my invention, together with the apparatus which I now consider to represent the best embodiment thereof, but I desire to have it understood that the invention described in the drawings is merely illustrative, and that the invention may be carried out in other ways without departing from the spirit of my invention.

Having now described my invention, 80 what I claim as new and desire to secure by Letters Patent of the United States, is:

1. A talking machine horn or resonator, comprising walls of more than three layers of fibrous material and a coating of non- 85 fibrous material.

2. A talking machine horn or resonator, comprising walls consisting of more than three layers of wood, the grain of adjoining layers being arranged at right angles to 90 each other, and a coating of non-fibrous material.

3. A talking machine horn or resonator, comprising walls consisting of more than three layers of wood, the grain of adjoining 95 layers being arranged at right angles to each other, and a coating of silicate of soda.

4. A talking machine horn or resonator, comprising walls consisting of more than three layers of wood, the grain of adjoining 100 layers being arranged at right angles to each other, and covering secured to the edges of the layers.

5. A talking machine horn or resonator, comprising walls of more than five layers 105 of fibrous material and a coating of non-fibrous material.

This specification signed and witnessed this 28th day of February, 1919.

JOSEPH WOLFF.
